GOLF CLUB HEAD

Anthony A. Viero, North Dartmouth, Mass., Edward R. Woolley, Rancho Santa Fe, Calif., and John W. Jepson, Marion, Mass., assignors to Acushnet Company

Filed July 15, 1971, Ser. No. 163,144

Term of patent 14 years

Int. Cl. D21—02

U.S. Cl. D34—5

FIG. 1

FIG. 2

— 4 —

FIG. 3

FIG. 4

FIG. 5

FIG. 6

FIG. 7

FIG. 8

FIG. 9

FIG. 1 is a front view of a golf club head.

FIG. 2 is a rear view of our new and ornamental design for a golf club head on a No. 3 iron.

FIG. 3 is an end view of the golf club head of FIG. 2.

FIG. 4 is a section view through line 4-4 of FIG. 2.

FIG. 5 is an end view of a golf club head having our new and ornamental design on a No. 6 iron.

FIG. 6 is a front view of a No. 9 iron.

FIG. 7 is a rear view showing our new and ornamental design on a No. 9 iron.

FIG. 8 is an end view of FIG. 7.

FIG. 9 is a section view of FIG. 7 through line 9-9.

The dominant feature of our design resides in the appearance of the rear portion of the club head.

We claim:

The ornamental design for a golf club head, substantially as shown and described.
